UNITED STATES PATENT OFFICE.

WILLIAM ROBINSON, OF BROOKLYN, NEW YORK.

BICYCLE.

13,690.

Specification of Reissued Letters Patent. Reissued Feb. 17, 1914.

Original No. 1,067,230, dated July 8, 1913, Serial No. 654,532. Application for reissue filed July 26, 1913. Serial No. 781,387.

To all whom it may concern:

Be it known that I, WILLIAM ROBINSON, a citizen of the United States, residing in Brooklyn, in the county of Kings and State 5 of New York, have invented a new and Improved Bicycle, of which the following is a specification.

My invention includes means for driving the machine without the intervention of a 10 chain.

It also includes an automatic brake mechanism.

The nature of my invention will be clearly understood from the description which follows, reference being had to the accompanying drawings, which form a part of this specification, in which—

Figure 1 is a side elevation showing the working mechanism of a bicycle embodying 20 the main features of my invention. Fig. 2 shows a portion of the reverse side of the bicycle, illustrating the application of the brake mechanism to the rear or driving wheel hub of the machine. Fig. 3 is a detail side view of the brake fixture, to be secured to the rear fork of the frame, and Fig. 4 is an edge or end view of the same; Fig. 5 is a plan view of Fig. 1; Fig. 6 is a similar view showing an alternative distribution of the driving mechanism; Fig. 7 is a side view, partly in section, of the ball-bearing eccentric, used in Fig. 6, and Fig. 8 is an edge view of the same, partly in section. Fig. 9 represents one end of the hub 30 of the driving wheel, showing the exterior of the brake mechanism attached thereto; Fig. 10 is a cross section through the dotted lines $x-x'$; Fig. 9, and Fig. 11 is a side view illustrating the brake clutch, partly in dotted outline. Fig. 12 is a vertical, longitudinal section of Fig. 9; Fig. 13 shows the brake clutch center, with its balls or rollers. Fig. 14 is a section through $y-y'$, Fig. 13. Fig. 15 is a side view showing the 40 brake clutch case with one side open, and Fig. 16 is an exterior edge view of the same inclosed. Fig. 17 shows one end of the driving hub provided with two driving clutches, identical in construction, arranged as in Fig. 1. Fig. 18 is a cross section on the line $z-z'$ Fig. 17, showing the interior construction of said driving clutch. Fig. 19 is a cross-section on the line $x'-x'$, Fig. 18, and Fig. 20 is a similar view showing an 50 incised bearing surface for the balls.

A represents a bicycle having the frame B provided with the cranks C, C' connected by the crank shaft a in any usual or suitable manner. The rear or driving wheel D, with its hub H, is also mounted in the frame B as shown. The upper portions of the bicycle frame are omitted for the purpose of illustrating more clearly the working parts.

The frame B is provided with the supplemental ball bearing hanger E, parallel 65 to the usual crank hanger K and conveniently located near the angle formed by the saddle post F and the lower rear fork sides $b-b'$, but preferably in the line of said saddle post, and rigidly secured thereto, or 70 forming a part thereof, as shown.

The hub H is provided with the clutches G, G' consisting essentially of the inner hardened ring c rigidly secured to the hub H, the outer-ring d provided with the inner 75 curving or wedged shaped recesses d' , and the balls or rollers e located within said recesses d' , between said rings c and d , and arranged to lock said rings together and to release the same, according to the relative 80 position of said balls within said recesses.

It is evident that when the clutch ring d is moved in the direction of the arrow z' the balls e are wedged between the fixed inner ring c and the outer ring d , locking said 85 rings together, and consequently the hub H is thus caused to revolve, that is, the driving wheel D is thus driven forward. It is also evident that when the outer ring d is moved in the reverse direction relatively to the hub H the balls e move to the widest ends of the recesses d' d' , thus releasing the grip between the said rings c and d and permitting them to revolve freely with reference to each other. Thus a to and fro movement of the 90 clutch ring d alternately clutches and releases the hub H. It will be observed also that when a revolving driving motion has been imparted to the wheel D if the clutch ring d be held at rest the hub H will continue to revolve freely within the same, that is, the driving wheel is always free to coast 95 forward without interference from the driving clutches.

As shown in Fig. 20 the clutch rings c and d are provided with grooves c'' d'' for the balls e thus giving the latter a greater frictional gripping surface.

The working parts of the clutch G are 100 enclosed by side plates e' .

The bearing clutch ring *c* is made separate from the hub *H* for convenience of hardening and replacing when worn. If the peripheral surface of the hub were suitable, it 5 might be used directly as a bearing surface for the clutch without the intervention of the separate ring *c*.

The crank shaft *a* is provided with the driving spur gear *I* which meshes with the 10 pinion *f*, which latter is mounted on the intermediate axle or countershaft *f'* revolving on ball bearings within the hanger *E*.

The connecting rod *i* has one end *h* pivotally connected to the crank *g* on the axle *f'* 15 as shown at *l*, while the opposite end *h'* is pivotally connected to the projection or lug *k* of the hub clutch *G'*, as shown at *l'*. In like manner the connecting rod *i'* (Figs. 1 and 5) has one end pivotally connected to 20 the rod *i* near the inner end *h* thereof, as shown at *m*, and its opposite end pivotally connected to the lug *k'* of the hub clutch *G*, as shown at *m'*. The clutches *G* and *G'* are 25 identical in construction, but, as shown in Figs. 1, 5 and 17, one is operated from above and the other from below the hub *H*.

The operation is as follows: When the gear *I* is turned forward by the movement of the cranks *C C'* the pinion *f*, with which 30 it meshes, is revolved in the reverse direction, thus revolving the axle *f'* with its crank *g*. The revolving of said crank *g*, as is evident, causes reciprocating movement in the driving rods *i, i'*. The backward movement of the rod *i* causes the clutch *G'* to grip the hub *H* and to revolve the same, driving the wheel forward, while the simultaneous backward movement of the rod *i'* releases the hold of the clutch *G* on the hub 40 and pushes said clutch backward to the position shown in Fig. 1, ready to take a new grip on said hub. As soon as the crank *g* passes its center the initial forward movement of the rod *i* releases the hold of the 45 clutch *G'* upon the hub *H*, and at the same instant the clutch *G* clutches said hub continuing the revolution of the same and the forward movement of the wheel. The clutch *G* retains its grip on the hub during the forward movement of the rod *i'*, that is, 50 throughout the forward half revolution of the crank *g* while during the same space the grip of the clutch *G'* is released from said hub. In like manner the grip of the clutch 55 *G* is released from the hub while the clutch *G'* clutches and retains its grip upon said hub, throughout the backward half revolution of said crank *g*. Thus the alternate clutching and releasing of the hub and reciprocating movement of said clutches *G G'* thereon produce a continuous forward movement of the driving wheel. It will be understood that when the driving wheel is in motion the stopping or slowing up of the driving 60 mechanism will allow the wheel to coast

at full speed, the hub turning freely within the clutches *G G'* which act upon the hub only in one direction and then only when the hub has a tendency to lag behind the driving mechanism. Since the driving wheel is thus free to coast it is necessary to provide means for controlling and stopping it. I therefore provide an automatic brâke applied to the hub and operated by back pedaling, as will be understood from the following specific description. 70

L is a barrel or drum secured to the hub *H* and revolving therewith. The fixture *n* is removably secured to the frame, being held in place by its projection *n'* engaging the jaws *o* of the rear forks *o'* and by the wheel axle *p* passing through the orifice *p'* of said fixture *n*. 75

One end of the expanding ring or device *q* engages or abuts against the outer end, or a shoulder *n''* of the fixture *n*, while the lug *r* is secured to, or engages, the opposite end of said expanding ring *q*. The latter, together with a portion of the fixture *n*, is inclosed within the said barrel or drum *L*, said expanding ring being normally located in close proximity to the inner peripheral surface of the barrel *L*, as illustrated, especially in Figs. 10 and 12. 80

The brake clutch *N* has its clutch center *s* 85 provided with grooves or recesses *s'* for the balls or rollers *t*, and is mounted rigidly on the axle *f'*, and, with its balls *t*, is inclosed peripherally by the clutch ring *M*, as shown. The clutch ring *M* is provided with the lug *t'*, and the lugs *r* of the brake and *t'* of the brake clutch mechanism are coupled together by the connecting rod *u* which has its opposite ends pivotally connected to said lugs as shown at *r', t''*. 90

The operation is as follows: When the wheel and the driving cranks *C C'* are moving forward the pinion *f* with its axle *f'* and the brake clutch center *s*, secured to said axle, are revolving in the reverse direction, 100 that is, in the direction of the arrow *y'*, Fig. 11. It is evident therefore that when the axle, are revolving in the reverse direction, described, the balls or rollers *t* are necessarily in the widest part of the recesses *s'* and 105 are pushed backward by the square or abrupt shoulders *t''* of the clutch center *s*, and said clutch center *s* revolves freely within the ring or case *M* without operating or affecting the brake. When, however, back pressure is applied to the driving cranks 110 the axle *f'* and clutch center *s* are of course revolved in the opposite direction, forcing the balls *t* into narrower portions of the recesses *s'* thus locking the clutch center *s* 115 and clutch ring *M* firmly together. The clutch ring *M* thus locked, is carried forward with the clutch center *s*, at the same time carrying forward the connecting rod *u* and thus expanding the ring *q* and causing 120

it to exert a braking frictional pressure against the inner periphery of the barrel or drum L.

It is evident that by regulating the back pressure on the pedals the braking pressure exerted by the brake mechanism can be regulated perfectly, and this brake may be operated with equal facility by a child or by a heavy man without any differential adjustment of the mechanism. Furthermore, as the leverage applied to the braking shaft f' is multiplied it is evident that, however fast the wheel may be traveling, as great braking pressure may be instantly applied, if desired, for stopping the wheel as is applied for driving the same.

The open face of the brake L is inclosed by the cap u' when said brake is in position, and, in like manner, the face of the clutch N is covered by the cap or case u''.

As shown in Fig. 6 the clutch G, with its connecting rod i', is transferred to the opposite side of the machine from that shown in Fig. 1. In this case the connecting rod i' is secured to the eccentric P mounted on the countershaft or axle f'. For the purpose of diminishing friction I prefer to make this eccentric P with a circumferentially grooved center v and the case v' with the balls w between them, thus forming a ball bearing eccentric.

In the arrangement shown in Fig. 6 the connecting rod i is connected to the lug k of the clutch G' above the hub H, and the crank g and the eccentric P are mounted on the axle f' with their longitudinal centers preferably in the same plane but on opposite sides of their axle f'. Thus the wheel D is driven by the alternate pulling movement of the connecting rods i i' upon their respective hub clutches G' G. This arrangement of connecting rods and clutches has the advantage that both of the connecting rods are located entirely above the rear fork sides b b', that both the driving clutches are located at equal distances from the center of the hub H and both of said connecting rods i i' do their work by pulling. On the other hand the eccentric construction described renders the driving mechanism perhaps somewhat more complicated than that illustrated in Fig. 1. When thought desirable, however, the driving hub may be provided with three or four driving clutches, two as shown in Fig. 1 and one or two on the opposite side of the machine connected to and operated by the eccentric P. In this way a uniform driving pressure may be applied to both ends of the driving hub simultaneously; or by "quartering" the crank and eccentric one clutch may be made to begin its work at the moment one on the opposite side has reached its maximum leverage and efficiency.

66 The clutches G G' are held in proper posi-

tion on the hub H by the shoulder a'' and the washers or nuts b''.

The brake mechanism shown in Figs. 10 and 12 is intended to illustrate a convenient device to be used in carrying out my invention, but I do not intend to limit myself to this particular form of brake, but may use other forms. In like manner I may use other forms of driving and brake clutches without interfering with the spirit of my invention.

It will be observed that in the hub clutch G the inner, annular ball seat c, that is, the revolving part of the clutch, is plain or regular in form, while the outer or driving part d of said clutch, is provided with ball or roller retaining recesses d'. On the contrary, in the brake operating clutch N the inner or revolving part s is provided with the ball-retaining recesses s', while the outer ring or case M has a plain or regular inner peripheral surface. That is, in each instance, the driving or power-transmitting part of the clutch is the part provided with the ball or roller retaining recesses.

It will be observed that when the crank gear is turned backward, in back pedaling, the gear meshing therewith is rotated forward, locking the braking clutch and drawing the brake rod forward as heretofore set forth. The forward movement of said rod draws the free end of the split brake ring forward as shown, whereby the pressure on the free end of said brake ring, in applying the brake, is exerted in a direction coinciding with the direction of forward rotation of the wheel. By this construction and arrangement the forward rotation of the wheel is caused to enhance the braking pressure of the brake applied thereto, since said forward rotation of the wheel tends to press the braking element forward against an unyielding fixture.

Having thus described my invention, what I claim as new and desire to secure by Letters Patent, is—

1. In a hub brake, a coasting wheel hub provided on its inner periphery with a braking surface, a non-rotatable fixture supported at one point by the stationary axle and provided with a projection for connection with the frame of the vehicle at a distance from said axle, a movable braking element held in non-rotatable position by said fixture, driving means, and means for forcing the outer surface of said movable element against said braking surface of the hub on reversing the movement of said driving means.

2. The combination of a stationary supporting shaft, a driving and coasting wheel hub rotatably supported thereon and provided with a driver, and on its interior with a braking surface, means for automatically clutching together said driver and hub for

- driving and releasing the same for coasting, a driving or crank shaft, a stationary fixture supported at one point by said supporting shaft and having an extension engaging the vehicle frame at a distance from said supporting shaft, a non-rotatable movable braking element held in position by said stationary fixture, said braking element coöperating with said braking surface to apply a brake thereto, and means for actuating said brake by the reverse movement of said driving or crank shaft.
3. In a hub brake, a coasting wheel hub provided on its interior with a braking surface, a stationary anchoring plate supported at one point by the wheel axle and arranged for connection with the frame of the vehicle at a distance from said axle, a movable braking element held in non-rotatable position by said anchoring plate, driving means, and means actuated by reversing said driving means, for forcing said movable braking element outwardly against said braking surface of the hub by pressure exerted upon said movable braking element in the direction of the forward rotation of said hub.
4. In a hub brake, a coasting wheel hub provided on its interior with a braking surface, a stationary fixture supported at one point by the wheel axle and engaging the frame of the vehicle at a distance therefrom, a movable braking element connected non-rotatably to said stationary fixture, a driving crank shaft, means for connecting said crank shaft to said hub for driving and disconnecting the same for coasting, means for pressing said movable braking element outwardly against said braking surface of the hub by the reverse movement of said crank shaft, and means for causing the direction of said pressure to coincide with the direction of the forward rotation of said wheel hub.
5. The combination of a stationary supporting shaft, a coasting wheel hub revolvably supported thereon and provided with an inner peripheral braking surface, a braking device embodying a spring braking member radially expansible and applicable to said braking surface of the hub, and means for supporting said spring braking member in non-rotatable position, driving means, means for expanding said spring braking member outwardly into braking contact with said braking surface of the hub on the reverse movement of said driving means, the contractile force of said spring braking member releasing said brake mechanism on the forward movement of said driving means.
6. A self-contained coaster-brake, comprising a rotary wheel hub, a braking surface thereon, a continuous stationary axle passing through said hub and projecting therefrom at each end, a brake-holder on the axle having means to engage a vehicle frame adjacent to the axle to prevent rotation of the brake-holder, a brake connected with the brake-holder and adapted to coöperate with said hub braking surface, a driver having rotative motion about the axis of said hub, and a releasable driving connection between the driver and the hub.
7. A self-contained coaster-brake, comprising a continuous stationary axle adapted to be fixed to the rear frame of a bicycle or similar vehicle, a rotary wheel hub mounted on the axle, a braking surface carried by said hub within such rear frame, a brake-holder on the axle independent of the frame of a vehicle, having means to engage such vehicle frame adjacent to the axle to prevent rotation of said brake-holder, a movable brake connected with the brake-holder and adapted to coöperate with said hub braking surface, a driver having rotative motion about the axis of said hub, and a releasable forward drive connection between the driver and the hub.
8. A self-contained coaster-brake, comprising a rotary wheel hub, a braking surface thereon, a continuous stationary axle passing through said hub and projecting therefrom at each end, a brake-holder on the axle having means to engage a vehicle frame adjacent to the axle to prevent rotation of the brake-holder, a band-brake adapted to coöperate with said braking surface and having one end connected with said brake-holder, a driver having rotative motion about the axis of said hub, and a releasable forward-driving connection between the driver and the hub.
9. Coaster-brake mechanism, comprising a rotary wheel hub, a braking surface thereon, a continuous stationary axle passing through said hub and projecting therefrom at the ends, a brake-holder on the axle having means to engage a vehicle frame to prevent rotation of the brake-holder, a brake connected with the brake-holder and adapted to coöperate with said hub-braking surface, driving means, a releasable driving connection between said driving means and the hub, and means actuated by reverse movement of the driving means for applying the brake.
10. In a bicycle, in combination, a coasting wheel hub having an inner braking surface, a stationary braking element, a movable braking element radially extensible against said braking surface of the hub and retained in non-rotatable position by said stationary element, driving means embodying a driving or crank shaft, means for actuating said brake mechanism on reversing the movement of said driving means, and means intermediate said driving means and said movable braking element to convert the backward pressure of said driving means.

into forward outward pressure when exerted upon said radially extensible braking element, in applying the brake.

11. In a bicycle a wheel hub having a braking surface at one side of its center, a driver at the opposite side of its center, a brake coöperating with said braking surface, a pivoted brake operating member angularly movable about its center in the direction of forward rotation of the wheel to apply the brake, a drive shaft and connections whereby pressure on the drive shaft in one direction rotates the wheel forwardly and means whereby back pedaling applies the brake.

12. A coaster brake mechanism comprising a wheel hub, a braking surface thereon, a continuous stationary axle passing through said hub and projecting therefrom at each end, said wheel hub having rotary motion about said axle, a brake supported in a braking position adjacent to said braking surface of the hub, means for applying said brake thereto and releasing the same therefrom, a driver having rotary motion about the axis of said hub, and a releasable driving connection between the driver and the hub.

13. A self contained coaster brake comprising a continuous stationary axle adapted to be secured non-rotatably in a fixed position in the frame of a bicycle or similar vehicle, a wheel hub mounted rotatably on said axle and provided with a braking surface, a brake means for supporting the same in a braking position adjacent to said braking surface of the hub and arranged to coöperate therewith the braking, means for applying said brake to said braking surface of the hub and releasing the same therefrom, a driver and a releasable driving connection between the driver and the hub.

14. A self contained coaster brake mechanism comprising a continuous stationary axle adapted to be secured non-rotatably in a fixed position in the frame of a bicycle or similar vehicle, means for securing the same in such fixed position, a wheel hub provided with a braking surface, a brake, means for supporting the same in braking proximity to said braking surface of the hub, said brake coöperating therewith for braking and controlling the operation of the wheel, means for controlling the application of the brake to said hub and releasing the same therefrom, a driver and a driving connection between said driver and the hub for driving when such driving connection is made, and

permitting the wheel to coast when disconnected from said driver.

15. A coaster brake mechanism comprising a rotary wheel hub having a braking surface, a continuous non-rotatable stationary axle passing through said hub and supporting the same rotatably, means for securing said axle rigidly in a non-rotatable position, a brake supported in normally released position in braking proximity to said braking surface of the hub, means for applying the brake to said braking surface of the hub for braking, and releasing the same for coasting, a driver, a releasable driving connection between said driver and the hub, for driving and releasing the same for coasting, and means whereby the brake may be applied by back pressure on the pedals.

16. A coaster brake mechanism comprising a continuous stationary axle, means for anchoring the same in a fixed, non-rotatable position in the frame of a cycle, a wheel hub having a braking surface and mounted rotatably upon said fixed axle, a movable brake member, means for supporting the same in a normally released braking position in proximity to said braking surface of the hub, a releasable driver, means for clutching said driver and hub together for driving and releasing the same to permit the free coasting rotation of the wheel, means for forcing said movable brake member into braking contact with said braking surface of the hub by pressure exerted upon said braking surface in the direction of the forward rotation of the wheel on releasing said driving means, thus utilizing the momentum of the forward rotation of the wheel for reinforcing the braking pressure of the brake thereon.

17. In a coaster brake mechanism, the combination of a wheel hub having a braking surface, a continuous stationary axle supporting said hub rotatably, means for anchoring said axle in a rigid non-rotatable position, a brake supported in a normally released position in braking proximity to said braking surface of the hub, a releasable driving connection operating to drive said wheel forward when connected thereto, permitting the wheel to coast when released therefrom, and means operating to apply the brake to said wheel when said driver is moved in the reverse direction.

WILLIAM ROBINSON.

Corrections in Reissue Letters Patent No.
13,690.

It is hereby certified that in Reissue Letters Patent No. 13,690, granted February 17, 1914, upon the application of William Robinson, of Brooklyn, New York, for an improvement in "Bicycles," errors appear in the printed specification requiring correction as follows: Page 5, line 35, after the word "brake" insert a comma; same page, line 38, for the article "the" read *for*; and that the said Letters Patent should be read with these corrections therein that the same may conform to the record of the case in the Patent Office.

Signed and sealed this 9th day of June. A. D., 1914.

[SEAL.]

J. T. NEWTON,
Acting Commissioner of Patents.
